ZIGZAG SEWING MACHINE

Ramon Casas Robert and Jean Court, Geneva, Switzerland, assignors to Mefina S. A., Binningen, Switzerland, a corporation of Switzerland

Application March 31, 1949, Serial No. 84,611
In Switzerland December 20, 1948

5 Claims. (Cl. 112—158)

1

In the known sewing machines fitted with a device for forming a so-called "zig-zag" stitch, not only a vertical reciprocating movement, but also a lateral rocking movement are imparted to the needle. The result is that the needle, when going down, is situated in front of different points of the rotary hook and the loop seizing beak of the latter comes and catches the loop, formed by the upper thread at the beginning of the upward stroke of the needle, either too early or too late, which causes the formation of irregular stitches or even misses, when the extent of the rocking lateral movement of the needle-carrier is large and when the needle is in too high a position during the passage of the beak of the rotary hook.

The present invention relates to a sewing machine fitted with a device for forming a "zig-zag" stitch, and in which the needle-carrier is actuated in a to and fro lateral movement synchronised with its vertical reciprocating movement. This machine aims at remedying the mentioned drawback by the fact that it includes a rotary hook, the rotation shaft of which is inclined in relation to the axis of the vertical displacement of the needle-carrier.

The attached drawing shows diagrammatically and by way of example a form of execution of the sewing machine in accordance with the invention.

Fig. 1 is a front view of same, certain parts of the casing being broken away.

Fig. 2 is a part cross-section view, illustrating the position of the rotary hook.

Fig. 3 is a perspective view of the actuating mechanism for the feeding means and of the actuating mechanism for the retaining stops of the rotary hook.

Fig. 4 is a profile view of the actuating mechanism for the feeding means.

Fig. 5 is a top view of the mechanisms housed in the lower arm of the sewing machine.

As shown on the drawing, the sewing machine includes a frame constituting a casing which contains all the actuating mechanisms for its various elements. This casing has a column 1, fixed on a lower arm 2 and bearing a needle-carrying arm. The latter is fitted at its end with a head 4 enclosing the mechanisms actuating the needle-carrier 5 and the thread-take-up (which is not shown) in reciprocable vertical movements. These mechanisms being not the object of the invention and being described in detail in co-pending applications, will not be described here. The needle-carrier 5 slides in

2

guides 6, 7 housed in the arms of a rocking support 8 having the general shape of a U and pivoting on a vertical axle 9, parallel to the needle-carrier 5. This rocking element is actuated in a rocking movement around its axle 9 by an actuating mechanism described in a co-pending application, so that the needle-carrier 5 is actuated in a to and fro lateral movement synchronised with its vertical reciprocating movement.

The lower arm 2 contains a rotary hook fixed on a shaft 11, which as shown is inclined at an angle substantially less than 90° and mechanically connected by transmission mechanisms to the main shaft P of the sewing machine. This rotary hook includes a revolving cup 10, fitted with a loop seizing beak 12, intended for snapping the upper thread loop which is formed on the side of the needle A at the beginning of the upward stroke of the latter. This cup contains a bobbin 14 (Fig. 3) kept fixed in a support 13. The latter includes two slightly inclined radial arms 15 and 16 which act alternately in conjunction with two mobile stops 17 and 18. These stops are carried by a lever having two arms 19, 32, rigidly connected together by a linking element 20, elastically articulated, by means of a blade spring 7, on a part 21 rigidly fixed to the frame of the machine. This part 21 is fixed by screws v to a bridge p which is itself rigidly fixed by screws V to the lateral walls of the lower arm 2. The lever 19, 32 is actuated in a regular rocking movement by a cam c, rigidly fixed on a driving shaft 22, mechanically connected to the main shaft P of the sewing machine.

The arm 2 further contains an actuating mechanism for the feeding means 23, including a support 24, connected to an actuating cam 25 by means of two levers, of which one, 26, is rigid and has a rocking movement in a horizontal plane, whilst the other, 28, is elastic and has a rocking movement in a vertical plane. The rigid lever 26 pivots on a vertical fixed shaft 27, while the elastic lever 28 is carried by a shaft 29 revolving in a bearing arranged in a support s rigidly fixed to the lower arm by fastening elements o. These two levers 26, 28 are arranged parallelly one to the other. This actuating mechanism for the conveyor being described in co-pending applications, will not be described in greater detail here.

The working of the described sewing machine is as follows:

The machine being in action, a regular vertical reciprocating movement is imparted to the

needle by a connecting rod 30 articulated on a crank pin 31 fastened to the main shaft of the sewing machine.

In addition, the rocking support 8 is driven in a rocking movement around its axle 9. These two movements of the needle-carrier are synchronised so that the lateral displacements of the needle take place during periods when the needle clears the cloth, as described in the mentioned co-pending applications.

The cup 10 of the rotary hook is actuated in a regular revolving movement, whilst the support 13 is kept immobile by the stops 17 and 18, alternately acting in conjunction with the arms 15 and 16. The upper thread *f* passes between the arm 15 and the stop 17, when the finger 32 acts in conjunction with the part *b* of the profile of the cam *c* and when the support 13 of the bobbin 14 is held against an angular displacement by the stop 18 acting in conjunction with the arm 16. On the contrary, the upper thread *f* can pass freely between the stop 18 and the arm 16, when the lever 19 is in the position shown on Fig. 3 and when the support 13 of the bobbin 14 is held against an angular displacement by the stop 17, acting in conjunction with the arm 15.

By examining Fig. 2, in which the needle A is shown in its middle position, the position which it would normally occupy for a straight seam, one notes that, the more it is displaced towards the right in relation to this middle position by the action of the device for forming the "zig-zag" stitch, the sooner the beak 12 of the cup 10, revolving in a clockwise direction, engages itself quickly in the loop formed by the upper thread on the side of the needle at the beginning of its upward stroke, and, on the contrary, that the more this needle is displaced towards the left in relation to its middle position, the later is the beak 12 in entering the loop formed by the upper thread. Now, when the revolving shaft of the rotary hook is situated in a plane containing the needle situated in its middle position, as is the case in the known sewing machines, and that, owing to this fact, the path followed by the beak 12 of the rotary hook is perpendicular to the displacements of the needle situated in its middle lateral position, and symmetric in relation to the plane containing the needle and the revolving shaft of the rotary hook, it may happen that, when the needle is displaced laterally from its middle position, the beak 12 passes too close to the hole of the needle, that is to say, when the needle has already gone back too high, it is no longer capable of engaging itself in the loop formed by the upper thread *f*. On the contrary, with the machine shown on the drawing, the shaft 11 of the rotary hook is not only situated in a vertical plane parallel with the needle-carrier and perpendicular to the advancement displacement of the feeding means, as is the case with certain known machines, but is in addition inclined in relation to the axis of the needle-carrier. The result is that the beak 12 is situated, when it passes in front of the needle A, at a greater distance from the resting surface for the cloth 34, when this needle is displaced towards the right in relation to its middle position, than when the needle is displaced towards the left in relation to this middle position. In consequence, this beak 12 is always capable of catching correctly the loop formed by the upper thread, the inclination of the shaft of the cup compensating, at least partly, the differences be-

tween the ascending strokes performed by the needle before the passage of the beak 12, which occur when the needle is in its extreme left or right position.

In order to give an easy access to the bobbin, a tipping-over cover is provided for. This cover includes two flaps 36 pivoting on pins 37 rigidly fastened to the frame. In addition, always with a view of facilitating access to the bobbin 14, said bobbin is arranged eccentrically in the cup 10.

One embodiment of the machine has been described here with reference to the attached drawing, given as an example, but it is obvious that many modified forms can be achieved. In particular, the actuating mechanisms for the needle-carrier, the feeding elements and the rotary hook can be of any other known types than those shown and described in the related patent applications.

We claim:

1. A sewing machine comprising a frame, a work feeder, a vertically reciprocable and laterally vibratable needle for the formation of a so-called "zig-zag" stitch and including a needle-carrier, an actuating mechanism imparting to said needle-carrier a vertical reciprocable movement and a lateral vibratory movement synchronized with its vertical reciprocable movement, a rotary hook mounted with its peripheral portion in close proximity to the path of travel of said needle, means rotating said rotary hook and a thread seizing beak on the peripheral portion of the rotary hook, the axis of the rotary hook being inclined at an angle substantially less than 90° relative to the axis of the vertical reciprocations of the needle carrier and the rotary hook being rotated in a direction that the beak will move upwardly in its thread seizing path of travel between the extreme positions of lateral vibratory movement of the needle.

2. A sewing machine as claimed in claim 1 in which the axis of the rotary hook is situated in a plane parallel to said needle carrier and perpendicular to the advancement displacements of the work feeder of the machine.

3. A sewing machine comprising a frame, a work feeder, a vertically reciprocable and laterally vibratable needle for the formation of a so-called "zig-zag" stitch and including a needle carrier, an actuating mechanism imparting to said needle carrier a vertical reciprocable movement and a lateral vibratory movement synchronized with its vertical reciprocable movement, a rotary hook including a revolving cup mounted with its peripheral portion in close proximity to the path of travel of the needle, means rotating said revolving cup, a thread seizing beak carried by said cup, the axis of the revolving cup being inclined at an angle substantially less than 90° relative to the axis of the vertical reciprocations of the needle carrier and the revolving cup being rotated in a direction that the beak will move upwardly in its thread seizing path of travel between the extreme positions of lateral vibratory movement of the needle, the axis of the revolving cup lying in a plane parallel to said needle carrier and perpendicular to the direction of feed of the work feeder, and a bobbin support eccentrically positioned in said cup.

4. A sewing machine comprising a frame, a work feeder, a vertically reciprocable and laterally vibratable needle for the formation of a so-called "zig-zag" stitch and including a needle

carrier, an actuating mechanism imparting to said needle carrier a vertical reciprocable movement and a lateral vibratory movement synchronized with its vertical reciprocable movement, a rotary hook including a revolving cup mounted with its peripheral portion in close proximity to the path of travel of the needle, means rotating said revolving cup, a thread seizing beak carried by said cup, the axis of the revolving cup being inclined at an angle substantially less than 90° relative to the axis of the vertical reciprocations of the needle carrier and the revolving cup being rotated in a direction that the beak will move upwardly in its thread seizing path of travel between the extreme positions of lateral vibratory movement of the needle, the axis of the revolving cup lying in a plane parallel to said needle.

carrier and perpendicular to the direction of feed of the work feeder, and a bobbin support eccentrically positioned in said cup, two arms extending radially from the bobbin support, a rocking lever mounted on said frame, two mobile stops carried by said lever for alternately cooperating with said arms to keep the support in a non-rotary position while permitting the thread of the needle loop to pass between said arms and stops.

5. A sewing machine as claimed in claim 3 and comprising a tipping-over cover pivotally mounted on the frame and covering said rotary hook.
